UNITED STATES PATENT OFFICE.

JACOB N. PATRICH, OF NEW YORK, N. Y.

DESIGN FOR A TEETHING RING.

60,947.

Specification for Design.

Patented May 9, 1922.

Application filed July 13, 1921. Serial No. 484,499. Term of patent 3½ years.

To all whom it may concern:

Be it known that I, JACOB N. PATRICH, a citizen of the United States of America, residing at No. 935 Kelly Street, borough of Bronx, in the city of New York, county of Bronx, and State of New York, have invented a new, original, and ornamental Design for a Teething Ring, of which the following is a specification, reference being had to the accompanying drawing, forming part thereof.

Fig. 1 is a front elevation of a teething ring showing my new design; and

Fig. 2 is a side elevation thereof.

I claim—

The ornamental design for a teething ring, substantially as shown.

JACOB N. PATRICH.
